ELECTRIC LIGHTING FIXTURE

Glenn E. MacFadden, Buffalo, N. Y., assignor to
 Markel Electric Products, Inc., Buffalo, N. Y., a
 corporation of New York

Application February 3, 1937, Serial No. 123,896

4 Claims. (Cl. 240—73)

This invention relates to improvements in electric lighting fixtures of the kind in which the light modifying means, namely the shades or diffusers, as the case may be, are removable.

One object of the invention is to provide for facility in applying and removing the light modifying means of the fixtures.

A further object is to provide a fixture in which the light modifying means is supported in such a manner as to avoid subjecting any part of it to an excessive strain.

A still further object is a fixture in which provision is made for preventing the light modifying means from canting or otherwise accidentally assuming an incorrect position or from vibrating in the fixture.

The invention is illustrated in the accompanying drawing in which:

Figure 1 is a view, partially in section and partially in elevation, of a fixture embodying the features of the invention.

Figure 2 is a section taken along line 2—2 of Figure 1.

Figure 3 is a section taken along line 3—3 of Figure 2.

Figure 4 is a fragmentary view of the light modifying means.

The fixture illustrated is of the so-called wall-bracket type. It includes an ornamental plate 7 which is adapted to be mounted upon a wall or other supporting surface over a suitable electrical outlet. The said plate is secured in such position by an element 8. It is formed with a neck 7a and carries a switch 9 for connecting the lamp 10 of the fixture to power. The light modifying means which is associated with the lamp 10 may be of any desired shape and may be formed from any suitable material. As illustrated, it comprises an inverted glass bowl 11 which is carried by the neck 7a and which is preferably translucent in order that a portion of the light from the lamp 10 will be permitted to pass through it and be diffused while the remainder of the light will be reflected toward the ceiling.

Means is provided whereby the bowl 11 may be attached and detached with facility. To this end the front wall 12 of the neck 7a is formed with an opening 13 for accommodating a T-shaped lug 14 which is formed or provided upon the bowl 11, the vertical leg of the said lug fitting in a reduced portion of the opening 13 while the horizontal arm is arranged between the side walls of a wider portion of the said opening. When the lug 14 is positioned in the opening 13 in the manner described the outer face of the

side wall of the bowl 11 fits conformably against the front wall of the neck 7a, the engagement of the walls of the opening with the vertical leg and the horizontal arm of the lug serving to hold the bowl from canting sidewise.

The bowl 11 is held in the position described by a clip 17 which is secured by a screw 18 to a cross-piece 19, the latter connecting the side walls 20 of the neck 7a and being located behind the upper portion of the opening 13. The clip 17, as best shown in Figure 2, is formed to provide diverging resilient arms 21 which extend forwardly through the opening 13 in the neck 7a and an aligned opening 22 which is formed in the side wall of the bowl 11 over the lug 14. Those portions of the arms 21 which extend into the bowl 11 are formed to provide reverse bends 23 which resiliently engage the inner face of the side wall of the bowl at opposite sides of the opening 22 and in the vicinity of the upper marginal edge 20 of the said wall, the terminal portions of the arms being bent forwardly to provide thumb or finger pieces 24.

The clip 17 is so designed that the reverse bends 23 act against the inner face of the side wall of the bowl to force the outer face thereof tightly against the adjacent wall of the neck 7a, whereby to hold the lug 14 in the opening 13 so that it will rest upon the bottom wall thereof to support the weight of the bowl. The pressure exerted against the side wall of the bowl by the reverse bends 23 is adequate to hold the said bowl tightly against the neck 7a and to prevent it from canting downwardly. Preferably the bottom of the vertical leg of the lug is slightly undercut, as illustrated, so that the bowl, when in its normal position, tends to move toward the neck 7a. It will be apparent, therefore, that the clip 17 and lug 14 co-operate to secure the bowl 11 tightly in the desired position, whereby to prevent the latter from canting or otherwise accidentally assuming an incorrect position or from vibrating in the position in which it is secured. It will be noted that the weight of the bowl is transmitted to the neck 7a in such a manner as to avoid subjecting any part of the bowl to an excessive strain. This is of particular advantage when, as in the present instance, the light modifying means is of glass.

In order to detach the bowl 11 the thumb or finger pieces 24 are forced toward one another against the spring action of the arms 21, whereby to move the reverse bends 23 away from and forwardly with respect to the engaged portions of the bowl 11. The latter, upon being released,

may be moved away from the neck 7a to withdraw the lug 14 from the opening 13, it being noted that the arms 21 are normally located a short distance above (Figures 1 and 3) the horizontal arm of the lug 14 in order that the opposite side of the bowl may, if desired, be tilted upwardly when the clip arms are held together in the manner described to facilitate withdrawal of the lug from the said opening. In attaching 10 the bowl the clip arms are squeezed together to permit the lug 14 to enter the opening 13, it being understood that in this operation also the opposite side of the bowl may, if desired, be tilted momentarily upwardly to facilitate entry of the 15 lug into the said opening. Thereafter when the clip arms are released the reverse bends 23 thereof move into engagement with the side wall of the bowl to secure the parts together in the manner described.

20 In the embodiment illustrated the socket 25 for the lamp 10 is carried by an arm 26 (Figures 1 and 3) which is secured to the cross-piece 19 by the screw 18, the said arm being supported over the clip 17 and extending substantially midway between the arms 21 thereof so that it will not interfere with the manipulation of the clip in the manner described. It is understood, of course, that the socket for the lamp 10 may be supported in any suitable manner, the construction shown being by way of illustration only. It is also to be understood that the invention is not limited to fixtures of the wall-bracket type but may be utilized to equal advantage in connection with ceiling and other types of fixtures.

35 I claim as my invention:

1. An electric lighting fixture including a lamp, a light modifying means associated with said lamp and having a wall, said wall carrying a lug and being formed to provide an opening, a support for said light modifying means, said support being formed to provide an opening to accommodate said lug and a clip which is carried by said support, said clip having resilient arms which extend through said first named opening and engage said wall to hold said lug in said last named opening, whereby to support said light modifying means in a predetermined position, said arms being yieldable to permit said lug to be withdrawn from said last named opening to enable said light modifying means to be detached from said support.

2. An electric lighting fixture including a lamp, a light modifying means associated with said lamp and having a wall, said wall carrying a lug and being formed to provide an opening which is located above said lug, a support for said light modifying means, said support being formed to provide an opening to accommodate said lug and a clip mounted behind said last named opening and having arms which extend through both of said openings to engage said wall to hold said lug in said last named opening, whereby to support said light modifying means in a predetermined position, said arms being yieldable to permit said lug to be withdrawn from said last named opening to enable said light modifying means to be detached from said support. 15

3. An electric lighting fixture including a lamp, an inverted bowl, a holder for said bowl, said bowl and holder having interfitting parts, a pair of diverging resilient fingers which extend across 20 said interfitting parts and which have portions which enter said bowl and engage the side wall adjacent said interfitting parts, whereby to support said bowl wholly by one side in a substantially horizontal position with said side wall directed upwardly, said fingers being accessible when said bowl is supported in the manner described and having extensions which must be grasped and manually moved toward one another to move said bowl engaging portions away from 25 said side wall and permit the bowl to be moved substantially horizontally in order to enable its detachment by separation of said interfitting parts. 30

4. An electric lighting fixture including a lamp, 35 an inverted bowl, a holder for said bowl, one of said last two named parts being formed with an opening and the other with a lug which fits in said opening and resilient means extending over said lug and into said bowl to engage the side 40 wall thereof above said lug, whereby to support said bowl wholly by one side in a substantially horizontal position with said side wall directed upwardly, said means having a part which is located adjacent the top edge of said side wall and which must be grasped and manually moved to deform said resilient means to permit the bowl to be moved substantially horizontally to withdraw said lug from said opening. 45
